BODY VIBRATOR

Robert R. Gonsett, Los Angeles, Calif., assignor of one-fifth to Buck Walker, Los Angeles, Calif., one-fifth to Wesley D. Spence, and nineteen-fortieths to Chester Ullom, Laura Ullom, Victor Ullom, and Charles Oxley

Application April 11, 1928, Serial No. 269,244
Renewed February 13, 1933

16 Claims. (Cl. 128—63)

My present invention relates to vibrators, particularly for vibrating the human body.

The objects of this invention are: first, to provide a vibrator of this class whereby a person 5 may vibrate any part of his body without assistance of others; second, to provide a vibrator of this class whereby a back and forth vibration may be obtained creating a fast rubbing effect; third, to provide a vibrator of this class whereby extremely light vibrations or extremely severe vibrations may be imparted to the body without change of the device, the intensity of the vibrations being varied by the person using the device by merely applying greater force on the portion 15 of the device connected with the body; fourth, to provide a device of this class which may be used either on the whole body or on any part thereof; fifth, to provide as a whole a novelly constructed vibrator; sixth, to provide a novel means for supporting the vibrator so that the same may be held 20 in any elevated position when in use, and when not in use, the current connected thereto may be automatically shut off; and, seventh, to provide a vibrating means of this class which is simple and economical of construction, durable, easy 25 to operate and to apply, and one which will not readily deteriorate or get out of order.

With these and other objects in view as will appear hereinafter, my invention consists of certain 30 novel features of construction, combination and arrangement of parts and portions, as will be hereinafter described in detail and particularly set forth in the appended claims, reference being had to the accompanying drawings and to the characters of reference thereon which form a part of 35 this application in which:

Figure 1 is a top or plan view of my vibrator in one form of construction, showing the same applied to the torso of a human body, certain 40 parts and portions thereof being broken away and in section to facilitate the illustration; Fig. 2 is a similar view of a slightly modified form of construction which is adapted to be gripped by the hand or applied around smaller portions of the body; Fig. 3 is a reduced side view thereof, showing the means of supporting the same on a bracket and the means for automatically shutting off the electric current;

Like characters of reference refer to similar 50 parts and portions throughout the views of the drawings.

The vibrator shown in Fig. 1 is provided with two electro-magnets A and B which are mounted on a unitary support 1. These electro-magnets 55 are of simple construction and are used with

ordinary commercial alternating current although other alternating current or interrupted direct current may be used, of much lower frequencies, if desired. Each of the electro-magnets consists of ordinary wire coils 2 which are 60 wound around tubes 3 made of brass or other non-magnetic metal or other material. The tubes 3 extend transversely through the opposite ends of the support 1 and are retained in position by nuts 4 and 5 at the opposite sides of the support. Both of the tubes and the coils wound thereon extend beyond the front side of the 65 support.

In the tube of the electro-magnet A is reciprocally mounted an iron core 6 which is provided 70 with a reduced stem 7 made of brass which extends beyond the front end of the tube. In the tube of the electro-magnet B there is also reciprocally mounted an iron core 8 which is also provided with a brass stem 9 which extends beyond the front end of the latter tube. Over the outer ends of the tubes 3 there are secured caps 10. Around the stem 7 and between the core 6 and the cap 10 there is positioned a compression spring 11 for normally forcing the core 75 6 inwardly and to the central portion intermediate the ends of the coil. Around the stem 9 and between the core 8 and the cap 10 there is also positioned a compression spring 12 but of heavier gauge and greater length than the spring 80 11. The spring 12 is adapted to force the core 8 toward the inner end of the tube beyond the central portion thereof. When outward force is applied to the cores, the core 6 is positioned outwardly from the central portion of the electro-magnet A and the core 8 is positioned inwardly 85 from the central portion of the electro-magnet B. When the electro-magnets are electrified the cores are immediately forced to the central portions intermediate the ends of the electro-magnets, provided a current of long enough duration 90 of alternation or interruption is employed.

At the outer ends of the rods or stems of the plunger cores 7 and 9 there are provided eyes 100 to which are detachably connected snap hooks 13 which are also provided with eyes connected to flexible cables 14. The other ends of the cables 14 are connected to a flexible band 15 which may be made of leather or metal of suitable weight and width so as to cover a proportionately large surface of the body.

The particular arrangement of the electro-magnets on the support is such that the distance 110 between the same is preferably that of the aver-

age width of the human body, a cross section of which is shown in Fig. 1, bearing against the inner side of the strap 15. It will be noted, however, that even though the width of the torso of the body or of any other member of the body bearing against the inner side of the strap 15 is greater or less than the distance between the electro-magnets, vibrations will nevertheless be imparted to the body. If desired, the electro-magnets A and B may be adjustably mounted 10 on the support 1 so as to vary the distance between the same.

When using the device upon the body, as shown in Fig. 1, the body is forced away from the device compressing the springs 11 and 12. The spring 11 being lighter than the spring 12 will be more easily compressed, permitting the core 6 to be drawn beyond the central portion of the electro-magnet, while the core 8 is positioned inwardly 20 beyond the central portion of the electro-magnet B. During each alternation of the electric current of sufficient low frequency (say 25 cycles), current passes through the coils B forcing the cores 6 and 8, or tending to force the same, toward the middle portion of the electro-magnets. It will be noted that the core 8 is positioned to compress the spring 12 when the current passes through the coil of the electro-magnet B, while the movement of the core 6 toward the middle portion of the electro-magnet is facilitated by 30 the spring 11. After this operation when the potential of the current falls to zero between the alternations, the spring 12 tends to force the core 8 inwardly and through connections 14 and strap 15—tends to draw the core 6 outwardly against the spring 11, tending to force the strap 15 in the opposite direction. Thus a vibratory motion is set up longitudinally in the belt, which vibration is imparted to the surface of the body. In the operation of my device, there is 40 set up in the belt reciprocations which do not necessarily coincide with the cycle of alternations of the current, especially if the commercial alternating current of so called 60-cycle frequency is employed. But the period of the springs will coincide with the alternations at either regular or irregular intervals and thus produce movements of the belt at intervals longer than the frequency of alternation of the current. 50 As pointed out in the objects of my invention, by pressure of the body against the belt more or less, the intervals of vibration may be made longer or shorter. At the longer intervals greater movement will be involved than at the shorter intervals. The pressure of the body will tend to vary the period of vibration, and the patient may check the pressure on the belt at the position where he finds the vibrations most nearly suited to the treatment required.

60 It will be here noted that both of the electro-magnets A and B may be energized at the same time, or either one independently. For this purpose, there are provided separate switches 16 and 17 on the supporting member 1. When only one of the electro-magnets are connected, the apparatus may be used in the same manner as described above but the vibrations will be more direct instead of imparting a back and forth vibration upon the skin. When the current is 65 connected to the electro-magnet A, a harder and more sudden impulse is imparted to the strap than when the electro-magnet B is connected, the impulse in the former being created by the electro-magnet, while in the latter it is created 70 by the spring.

75

At the back side of the supporting member 1 and intermediate the ends thereof, is secured a supporting member 18 in the form of a hook having a latch 18a. This hook may be extended through and pivotally mounted on an eye of a slide 19 which is shiftably mounted in a vertical direction on a vertically positioned rod 20a of the U-shaped supporting bracket 20 which may be secured at its ends to a plate 21 adapted to be secured to a wall C, as shown in Fig. 3. The guide portion 20a may be provided at its inner side with spaced notches 20b beveled at its ends into which are adapted to be extended beveled lugs 19a within the slide 19. The slide is adapted to be retained in its vertically shifted position by the lugs 19a when force is applied on the strap 15 or other means tending to exert an outwardly directed force on the device. As soon as the outwardly directed force is released, the slide 19 is adapted to drop downwardly by gravity to the lower end of the guide portion, the lugs 19a clearing the notches 20b by reason of their beveled construction. On the lower supporting arm 20c of the bracket 20, I have provided a switch 22 which is provided with an outwardly extending shiftable switch arm 22a the outer end of which is positioned around or contiguous to the guide portion so that when the slide 19 is lowered by gravity, when the device is not in use, the current is automatically shut off. A flexible electric cable extends from this 22, as indicated by 23, to the supporting member 1 and is adapted to be connected thereto by a detachable plug and socket 24.

In the modified form of construction of my device, shown in Fig. 2, the electro-magnet is 110 preferably the same as the electro-magnet A and is provided with a similarly constructed and operated reciprocal plunger core and spring. In this construction, which consists of only a single 115 electro-magnet, the supporting member is secured directly to the end of the electro-magnet by the supporting member 18 also in the form of a hook. In this construction also there is provided at the end of the cable 14 a hand grip 25 which may be gripped by the hand and drawn outwardly so that vibrations may be imparted to the body through the hand. This hand-grip, however, may be replaced by a strap for encircling 120 any portion of the body for imparting vibration 125 thereto.

Though I have shown and described a particular construction, combination and arrangement of parts and portions of my vibrator, and certain modifications thereof, I do not wish to be 130 limited to this particular construction, combination and arrangement, nor to the modifications, but desire to include in the scope of my invention the construction, combination and arrangement substantially as set forth in the appended claims. 135

Having thus described my invention, what I claim as new and desire to secure by Letters Patent is:

1. In a body vibrating device, a pair of hollow electro-magnets positioned parallel to and in 140 spaced relation relative to each other, a core reciprocally mounted in each of said electro-magnets, springs positioned in said electro-magnets adapted to force said cores towards the inner ends thereof, and a body contact member, each 145 core being operatively connected to a respective end of said body contact member, said body contact member being adapted to be drawn outwardly against the force of said springs, the one core being adapted to be drawn outwardly beyond 150

- the central portion of its enclosing electro-magnet, while the core within the other electro-magnet is positioned inwardly beyond the central portion of the other electro-magnet.
5. 2. In a body vibrating device of the class described, an electro-magnet, a core reciprocally mounted therein and provided with a portion extending beyond the one end of the electro-magnet, a compression spring positioned between the outer end of the electro-magnet and said core, another electro-magnet positioned in spaced apart relation relative to the first electro-magnet and extending in the same general direction, a core reciprocally mounted in said second electro-magnet and also provided with a portion extending beyond the forward end thereof, a second spring positioned between the outer end of said second electro-magnet and the core therein, and a body contact member connected to the extended portions of each of said cores adapted to draw the same outwardly against the action of said springs, the first core when drawn outwardly being positioned outwardly from the central portion of the first electro-magnet and the core in the second electro-magnet when drawn outwardly being positioned inwardly from the central portion of the second electro-magnet.
3. In a body vibrating device of the class described, an electro-magnet, a core reciprocally mounted therein and provided with a portion extending beyond the one end of the electro-magnet, a compression spring positioned between the outer end of the electro-magnet and said core, another electro-magnet positioned in spaced apart relation relative to the first electro-magnet and extending in the same general direction, a core reciprocally mounted in said second electro-magnet and also provided with a portion extending beyond the forward end thereof, a second spring of greater strength than the first mentioned spring positioned between the outer end of said second electro-magnet and the core therein, and a body contact member connected to the extended portions of each of said cores adapted to draw the same outwardly against the action of said springs, the first core when drawn outwardly being positioned outwardly from the central portion of the first electro-magnet and the core in the second electro-magnet when drawn outwardly being positioned inwardly from the central portion of the second electro-magnet.
4. In a body vibrating device, a unitary support, electro-magnets mounted at the opposite ends of said support and extending to one side thereof, a body contact means operatively connected to each of said electro-magnets, and supporting means intermediate the ends of said unitary supporting member.
5. In a body vibrating device, a unitary support, electro-magnets mounted at the opposite ends of said support and extending to one side thereof, body contact means operatively connected to each of said electro-magnets, supporting means intermediate the ends of said unitary supporting member, and separate electric switches connected to each of said electro-magnets for separately controlling the same.
6. In a body vibrating device, a unitary support, electro-magnets mounted at the opposite ends of said support and extending to one side thereof, body contact means operatively connected to each of said electro-magnets, supporting means intermediate the ends of said unitary supporting means, separate electric switches connected to each of said electro-magnets for separately controlling the same, and a vertical supporting bracket upon which said supporting means is vertically shiftably mounted.
7. In a body vibrating device, a unitary support, electro-magnets mounted at the opposite ends of said support and extending to one side thereof, body contact means operatively connected to each of said electro-magnets, supporting means intermediate the ends of said unitary supporting means, separate electric switches connected to each of said electro-magnets for separately controlling the same, a vertical supporting bracket upon which said supporting means is vertically shiftably mounted, and a switch means at the lower end of said bracket adapted to be engaged by said supporting means for automatically shutting off the electric current to the electro-magnet when the device is lowered.
8. In a body vibrator, a vertical supporting bracket having a plurality of notches therein spaced one above the other at its inner side, a slide reciprocally mounted on said bracket and provided with lugs adapted to extend into said notches when the slide is drawn outwardly, a body vibrating means mounted on said slide, and a switch means at the lower end of said bracket adapted to be engaged and operated by said slide when the same is lowered.
9. In a body vibrator, an electro-magnet, a core reciprocally mounted therein, a compression spring adapted to force said core into said electro-magnet, and a body contact member operatively connected to said core adapted to draw the core outwardly against the compression of said spring beyond the central portion of said electro-magnet.
10. In a body vibrator, an electro-magnet, a core reciprocally mounted therein, a compression spring positioned within the electro-magnet between a shoulder at the outer end thereof and the adjacent end of said core and adapted to force said core into said electro-magnet, and a body contact member operatively connected to said core adapted to draw the core outwardly against the compression of said spring beyond the central portion of said electro-magnet.
11. In a body vibrator, a pair of electro-magnets positioned in spaced apart relation, each comprising a coil and relatively movable core, and a body contact member operatively connected at its ends to respective cores of said electro-magnets.
12. In a body vibrator, a pair of spaced apart electro-magnets having armatures movable in opposite directions when the electro-magnets are simultaneously energized, a strap operatively connected at its ends to respective armatures of said electro-magnets, and means for returning the armatures to their normal position, the opposite ends of said strap being simultaneously shiftable in opposite directions.
13. In a body vibrator, a pair of electro-magnets positioned parallel to and in spaced relation relative to each other, said electro-magnets having armatures movable in opposite directions when the electro-magnets are energized, a vibrating member operatively connected at its opposite ends to respective armatures to be simultaneously vibrated in opposite directions at its opposite ends and means for returning the armatures to their normal position for causing a movement of the vibrating member in a direction opposite to that caused by the electro-magnets.
14. In a body vibrating device, a pair of electro-magnets positioned parallel to and in spaced

relation relative to each other, cores reciprocally mounted in each of said electro-magnets and shiftable in opposite directions thereby, means for returning the cores to their normal position, and a body member connected at respective ends to said cores.

15. In a body vibrating device, a pair of electro-magnets positioned parallel to and in spaced relation relative to each other, cores reciprocally mounted in each of said electro-magnets and shiftable in opposite directions thereby, a body member connected at respective ends to said cores, and spring means for forcing said cores inwardly from their positions and one of the

cores to the inner end of its associated operating coil.

16. In a body vibrating device, a pair of electro-magnets positioned in spaced apart relation and extended in the same general direction, each comprising a coil and an armature, the armature of one electro-magnet moving in opposite direction from the armature of the other, a body contact member operatively connected at its ends, to respective relatively movable armature of said electro-magnets and means for moving the armatures to their normal positions.
